UNITED STATES PATENT OFFICE.

ROBERT HOPE-JONES, OF NORTH TONAWANDA, NEW YORK, ASSIGNOR TO THE RUDOLPH WURLITZER MANUFACTURING COMPANY, OF NORTH TONAWANDA, NEW YORK, A CORPORATION OF NEW YORK.

STACCATO MECHANISM FOR MUSICAL INSTRUMENTS.

1,115,541.

Specification of Letters Patent.

Patented Nov. 3, 1914.

Application filed December 27, 1910. Serial No. 599,429.

To all whom it may concern:

Be it known that I, ROBERT HOPE-JONES, of North Tonawanda, in the county of Niagara and State of New York, have invented certain new and useful Improvements in Staccato Mechanism for Musical Instruments; and I do hereby declare the following to be a full, clear, and exact description of the same, reference being had 10 to the accompanying drawings, forming a part of this specification, and to the reference-numerals marked thereon.

My present invention relates to musical instruments and more particularly to organs 15 and it has for an object to provide an improved means for automatically producing a staccato effect upon the pipes or other sound producing elements of the organ.

A further and principal object of the invention is to enable the operator to obtain the effect of a staccato note upon one pipe simply by the depression of a single key on the manual, which pipe may be sounded in unison with one or more other pipes 25 coupled with it or otherwise under the control of that key, and capable of producing a sustained tone or tones while the key is held depressed.

To these and other ends the invention consists in certain improvements and combinations of parts all as will be hereinafter more fully described, the novel features being pointed out in the claims at the end of the specification.

In the drawings: Figure 1 is a partially diagrammatic view of a pair of organ pipes and their playing system, constructed in accordance with and illustrating one embodiment of my invention, the view showing in 35 section the operating and controlling mechanism of each pipe, and Fig. 2 is a detail of the contacts of a circuit breaker.

Similar reference numerals throughout the several figures indicate the same parts.

The musical effects which I seek to produce have been only approximated hitherto by executing with one hand the staccato note or notes, (dependent for their uniformity and sharpness entirely upon the 45 dexterity with which the keys are played) a very short, quick note of this kind on certain of the pipes or elements approaching in the character of its tone the picking or twanging of a stringed instrument, and in

effecting this with one hand while with the other a sustained tone is produced by the prolonged depression of another key on the same or a different manual. In simplifying and at the same time improving the effect of such manipulation, I provide the 50 hereinafter described arrangements comprising, in the present instance, a combination of pneumatic and electrical devices, the latter of which, it will be understood, are represented in a purely diagrammatic manner and as simply as is consistent with the results to be obtained although in the structure of a modern organ there are used, in place of the parts represented, complicated devices that perform various functions other 55 than those that enter into or will best aid in giving an understanding of the combinations of the present invention.

Referring more particularly to the drawings, I have shown, in the present embodiment, a pair of organ pipes 1 and 2 which are supplied with air at 3 and 4 according to the opening and closing movements of valves or pallets 5 and 6 from wind chests 8 and 9. The valves are held normally closed by springs 10 and 11 and are opened through connecting members 12 and 13 by the collapsing of bellows 14 and 15 arranged in the respective wind chests and exhausted through passages 16 and 17 and ports 18 and 19. 60 These ports are controlled by valves 20 and 21 also common to ports 22 and 23 opening into the wind chests by means of which the bellows are inflated through the same passages and these valves are connected to bellows 24 and 25 exposed to the interior of the chests and having communicating passages 26 and 27. Electromagnetic primary valves 28 and 29 control these passages being preferably constructed in accordance 65 with the disclosure of my prior application, No. 572,082, filed July 15, 1910, and hence they are not shown and will not be described in detail herein. Suffice it to say that when the magnets 30 and 31 are energized the valves are opened exhausting the two bellows in each wind chest and opening the pallets 5 and 6 to sound the pipes.

A playing key 32 carries a finger 33 which, when the key is depressed, connects the contacts 34 and 35 and closes a circuit a, b that includes the coil of the electromagnet 30 comprised within the operating

mechanism of the pipe 1, and is supplied with energy in any suitable manner as by the generator A. It will thus be seen that continued depression of this key will hold 5 the affected valves open and produce a sustained tone in the pipe 1.

A second key 36, on another manual we will say, carries a finger 37, which, when that key is depressed, connects the contacts 10 38 and 39 and closes a circuit that includes the coil of the electromagnet 31 comprised within the operating mechanism of the pipe 2. This circuit leads from one brush B of the generator A through wire c, contacts 15 38 and 39, wires d, e, f, g, magnet 31, wires h, i, contacts 40, 45 and 41, (which will be later described in detail) wire j and thence back through wire k to the brush C of the generator. Interposed, however, within this 20 last mentioned circuit is a circuit-breaker also actuated by the depression of key 36 so that the operating mechanism of pipe 2 is also under the control of this circuit breaker when the key is depressed. It comprises, in 25 the present instance, a wind chest or pressure chamber 42 containing a bellows 43 controlled by a valve 44 in exactly the same manner, if preferred, as the bellows 24 and 25, said valve comprising an electromagnet 44^a. 30 The bellows 43 carries a contact 45 (Fig. 2) which, when the bellows is expanded as is normally the case, connects the contacts 40, 41 in the circuit of the operating mechanism of pipe 2, and when the bellows is collapsed through the energizing of the magnet 44^a rises and breaks the circuit through these 35 contacts.

The magnet 44^a of the circuit-breaker is energized, as before stated, through the depression of key 36 by a circuit leading from 40 brush B of the generator through wire c, contacts 38, 39, wires d, e, l, the coil of magnet 44^a, wire m, and thence through wire k back to brush C. Thus the magnet breaks 45 the circuit at the contact 45 of the operating mechanism for pipe 2 with the result that when the key 36 is operated, regardless of the length of time it is held depressed, the pipe 2 will send forth only a very short, 50 quick tone resembling a staccato note and all notes thus struck will be mechanically uniform. The electromagnet 31, of course, acts instantly to open the bellows 15 to the atmosphere and as the latter is relatively 55 small, it in turn acts almost instantly to open the pallet 8 and though the magnet 44^a and the bellows 43 are of approximately corresponding sensitiveness, there is yet time for the opening of the pallet 8 to become 60 effective in the pipe 2, due in part to the lagging of the mechanical devices set in motion by the last mentioned magnet. In other words, the devices controlled by the magnet 31 are at least equally as fast as 65 those controlled by the magnet 44^a that

break the circuit to the first mentioned magnet, and therefore the prompt and positive actuation of the former is as much to be relied upon as the interrupting effect of the latter, as both circuits are closed simultaneously. Of course, should it be desired to sound pipe 2 in the usual manner, the operating mechanism could be disconnected from the control of the circuit breaker by a suitable device interposed in the circuit of the latter and having the function of a switch in which instance the bellows 43 would remain in its normal, expanded position and allow the contact 45 that it carries to remain at rest upon the contacts 40 and 41.

As thus far described, the continued depression of key 32 produces a sustained tone in pipe 1 while similar manipulation of key 36 provokes only the short note or staccato effect from pipe 2. Therefore, the simultaneous depression of both keys will give accompanying sustained and staccato tones. But two hands are still required for the operation although the delicate and rapid fingering of one of them is done away with. To enable the performer to do the same thing with one hand on a single key, the key 32 for instance, is so fitted as to enable it to also close the circuits of key 36, that is, through the operating mechanism of pipe 2 as well. To this end it is provided, in the present simplified construction, with a second finger 46 which connects contacts 47 and 48 bridged to the circuits of the key 36, the former by a wire n leading from brush B of the generator thereto, and the latter through wires o, p to the wire l. The finger 46 causes the joint sounding of the two pipes, with the depression of the one key, but it does this only, however, when a coupler D is drawn; so the two operating systems may be retained independent of each other except when the particular effect outlined is desired. This coupler D has been represented, in the present instance, merely as a switch as that is its real function herein.

I claim as my invention:

1. In a musical instrument, the combination with a tone-producing element and means for sounding the same, of a device controlling said sounding means and capable of rendering the latter inoperative when the said device is itself operated, a manual key, and operating connections between the key and both the sounding means and the controlling device arranged to operate them successively in the order named with a single actuation of the key.

2. In a musical instrument, the combination with a tone producing element, means for sounding the same and an electrically actuated device including a switch controlling said sounding means and capable of

- rendering the latter inoperative when the circuit through said device is closed, of a playing key, operating connections between the latter and the sounding means whereby the latter is operated by a single movement of the key, the switch of the electrically actuated device being arranged to be operated by the same movement of the key to close the circuit through the controlling device.
3. In a musical instrument, the combination with a tone producing element and sounding means therefor embodying an electrically-actuated device, of an electric device controlling said sounding means operable to break the circuit through the electrically actuated device thereof and thereby render the sounding means inoperative, and a playing key embodying jointly operable switches arranged in the circuits of both devices for closing the circuit through the electrically actuated device and the circuit through the controlling device with one actuation.
- 25 4. In a musical instrument, the combination with a tone producing element, electro pneumatic sounding means therefor, and a playing key for closing the circuit through the latter, of a switch in said circuit, a bellows for operating one of its contacts to break the circuit and render the sounding means inoperative, means for supplying operating pressure to the bellows and an electrical device controlling said supply and
- having its circuit closed by the actuation of 35 the key.
5. In a musical instrument, the combination with two tone-producing elements, a playing key and means for sounding one of them continuously while the key is depressed, 40 of means for sounding the other by the same depression of the key, a controlling device for interrupting the operation of the last mentioned means and connections from the key to said device for operating it by the 45 aforesaid depression of the key jointly with the operation of said last mentioned means.
6. In a musical instrument, the combination with two sound-producing elements, a playing key and means for operating one of 50 them continuously while the key is depressed, of operating means for the other including an electrically actuated device, having its circuit closed by the depression of the key, an electrical controlling device 55 for the last mentioned operating means embodying a switch located to break the circuit through the electrically actuated device, means embodying an electrical device for operating the switch, and connections between 60 the last mentioned means and the key for operating the switch-operating means by the same depression of the key.

ROBERT HOPE-JONES.
